[57] **CLAIM**

The ornamental design for a display rack, as shown and described.

DESCRIPTION

FIG. 1 is a perspective view of a display rack showing my new design;

FIG. 2 is a front elevational view;

FIG. 3 is a right side elevational view, the left side elevational view being a mirror image thereof;

FIG. 4 is a top plan view;

FIG. 5 is a bottom plan view; and,

FIG. 6 is a perspective view of a second embodiment of FIG. 1, the only difference being the addition of three adjoining display racks, it being understood that all the other surfaces are the same as shown in the embodiment of FIG. 1.

The broken line structure and boundaries shown in FIGS. 1, 2, 3, 4, 5 and 6 form no part of the claimed design.
